[57] CLAIM

The ornamental design for an air control check unit for fireplaces and the like, as shown and described.

DESCRIPTION

FIG. 1 is a perspective view of an air control check unit for fireplaces and the like, showing my new design; FIG. 2 is a top plan view thereof;

FIG. 3 is an elevational taken from one side thereof, the opposite side being a mirror image of the side shown; FIG. 4 is an end elevation thereof, viewed from the left of FIG. 3;

FIG. 5 is an elevational taken from the end opposite that shown in FIG. 4; and

FIG. 6 is a bottom view thereof.
